UNITED STATES PATENT OFFICE.

HENRY HOLUB, OF LOUISE, TEXAS.

HORSE-RELEASER.

1,092,993.

Specification of Letters Patent. Patented Apr. 14, 1914.

Application filed February 15, 1913. Serial No. 748,657.

To all whom it may concern:

Be it known that I, HENRY HOLUB, a citizen of the United States, residing at Louise, in the county of Wharton and State of Texas, have invented certain new and useful Improvements in Horse-Releasers, of which the following is a specification, reference being had therein to the accompanying drawing.

10 This invention relates to horse releasers, and the principal object of the invention is to provide a device which may be used for releasing the horses in case they become unmanageable and run away.

15 Another object of the invention is to provide an improved mechanism for operating the pins engaging the ends of the traces.

20 Another object of the invention is to provide an improved type of operating means 20 which will also release the hold back straps of a single harness.

25 With these and other objects in view this invention consists of certain novel combinations, constructions, and arrangements of parts as will be hereinafter fully described and claimed.

30 In the accompanying drawings: Figure 1 is a top plan view of a vehicle of the one horse type provided with the improved mechanism. Fig. 2 is a longitudinal sectional view through the swing tree shown in Fig. 1. Fig. 3 is a sectional view through one of the housings mounted upon the shafts shown in Fig. 1.

35 By referring to the drawings it will be seen that 40 designates a vehicle provided with the shafts 41 connected at their inner ends by the usual cross bar 42. The swing tree 43 is supported by the bracket 44 and 40 is provided with recesses 45 and with openings 46 in which the securing pins 47 are mounted. This swing tree is also provided with the spring housing 48 in which the springs 49 are mounted and the pins 47 are 45 provided with operating stems 50 extending through openings 51. Bell crank levers 52 are pivotally mounted upon brackets 53 and are connected by the links 54 with the springs 55, which springs are connected with 50 the inner end portions of the stems 50. Rods 56 extend inwardly from the bell crank levers 52 and are connected with the plate 57 which connects the rods 56 with the rod 58 extending through the dash board and

connected with one end of the treadle 59 normally held in the position shown in Fig. 1 by the springs 60. Rods 61 extend from the bell crank levers 52 and are connected with the bell crank levers 62 mounted upon the shafts 41. These bell crank levers 62 are 60 connected with the rods 63, which rods are connected with the stems 64 leading from the pins 65 slidably mounted in the housings 66 secured to the shafts. These housings are provided with pockets 67 in which springs 65 68 are mounted so that the pins 65 will be normally held in the position shown in Fig. 3, thus permitting the hold back straps 69 to be engaged by the pins 65.

When this type of device is in use the 70 traces 70 are engaged by the pins 47 and the hold back straps 69 are wrapped about the shafts and engaged by the pins 65. When it is desired to release the horse the treadle 60 is pressed by the foot of the driver and 75 this will draw the rod 58 inwardly to rock the bell crank levers 52, and thus draw the links 54 and rods 61 toward the center of the cross bar 42. When this happens the stems 50 will be moved against the tension 80 of the springs 49 to release the traces 70 and the bell crank levers 62 will be rocked to draw the rods 63 rearwardly and move the pins 65 against the tension of the springs 68 to release the hold back straps 69. 85

Having thus described the invention what is claimed as new, is:-

A device of the class described comprising a pair of shafts, a connecting bar for said shafts, bell crank levers connected with said shafts, a swing-tree connected with said connecting bar, brackets carried by said bar, bell-crank levers pivotally connected upon said brackets, back-strap engaging pins slidably connected with said shafts, lines connecting said back-strap engaging pins with said bell-crank levers of said shafts, rods connecting said bell-crank levers of said shafts with the bell-crank levers of said connecting bar, said swing-tree provided with an elongated socket at each end thereof, said socket terminating in a reduced pin receiving socket at one end, said swing-tree also provided with a notch upon one side thereof communicating with said first mentioned socket, an angle pin working in said socket and provided with a projecting portion working in said slot, a coil spring positioned 100

within said socket and wound upon said angle pin, said coil spring normally exerting an outward pressure upon said pin, rods engaging said angle pins, a spring carried by 5 said rods, said spring connected to said bell-crank levers of said connecting bar, and means for operating said bell-crank levers of said connecting bar for moving said trace

engaging pins and also moving said back-strap engaging pins.

In testimony whereof I hereunto affix my signature in presence of two witnesses.

HENRY HOLUB.
